UNITED STATES PATENT OFFICE

2,389,884

APPARATUS FOR TRANSMITTING VOICE FREQUENCIES OVER A SINGLE GROUNDED LINE

Ernest E. York, Auburn, Maine, assignor to Stanley Dana Corp., Portland, Maine, a corporation of Maine

Application May 12, 1944, Serial No. 535,243

6 Claims. (Cl. 179—3)

My present invention relates to apparatus for use in transmitting audio voice frequencies over single, grounded telegraph lines without interfering with the use of the telegraph instruments.

In certain organizations of which railroads afford one of the best examples, the stations, control towers, yard offices and other control points are generally serviced by a telegraph system to provide communication between such points. Telephones sometimes are also provided making it possible for the operator at any one control point to talk with the operator at another control point over existing telephone lines if the necessity arises.

It has been recognized for some time that such means of inter-location communication were not adequate because of insufficient flexibility in service offered and in operation to meet all requirements. Among the desired factors may be noted the necessity of rapidity in communication, of communicating by voice simultaneously with several stations, and of having a system variable as to its power to ensure adequate transmission and reception under variable and adverse conditions.

In accordance with my invention, I provide apparatus consisting of a pre-amplifier and a main amplifier connected to a suitable power source. The transmitting circuit, connected to the telegraph line and its ground, includes a voice transmitted and the pre-amplifier, while the receiving circuit also connected to the telegraph line and its ground consists of a voice filter, and voice receiver means. I provide switch mechanism to include the main amplifier either in the transmitting circuit or the receiving circuit to complete them and the telegraph line has bypass filters between stations and inductance coils at terminal stations to prevent voice currents from interfering with the normal use of the telegraph instruments.

Where the voice receiving circuit includes a voice receiver situated in a public part of a station, for example, I provide means for including such a voice receiver in the apparatus at the sender's option.

In accordance with my invention, I, therefore, provide means by which any operator at any station can talk with other stations without interference with telegraphic service while permitting him to control the receivers to be used. As the apparatus may be adjusted to ensure effective transmission and reception under any circumstances, my invention is well adapted to meet

the requirements of inter-station or other inter-location communication.

In the accompanying drawings, I have shown diagrammatically an embodiment of my invention from which its novel features and advantages will be readily apparent.

In the drawings:

Fig. 1 shows diagrammatically an inter-location communication system in accordance with my invention, and

Fig. 2 is a similar view of the apparatus at each station.

At 10, I have indicated a single, grounded telegraph line having stations 11 at each of which are located telegraph instruments. As these may be conventional, I have not shown these instruments, but have indicated at 12 the usual telegraph line relay. I place bypass filters 13 in the line 10 between each of the stations 11 to prevent voice frequencies from interfering with the normal use of the telegraph instruments. At terminal stations, the line 10 has inductance coils 14 to prevent voice currents from entering the circuits of the batteries 15.

Each of the locations or stations 11 is provided with audio transmitting and receiving apparatus. Such apparatus consists of a power supply generally indicated at 17 and consisting of a transformer 18 and a power rectifier 19 having a circuit 20 and a circuit 21.

The circuit 20 is the power supply circuit to a pre-amplifier 22 and a main amplifier 23, while the circuit 21 includes a relay 24 and a switch 25. The relay 24 is in control of switch mechanism generally indicated at 26.

One arm 27 of the switch mechanism 26 is adapted to connect either the voice transmitting circuit 28 or the voice receiving circuit 29 to the main amplifier 23. The other arm 30 of the switch mechanism 26 is adapted to connect either the lead 31 or the receiver circuit 32 to the main amplifier 23.

The arms 27 and 30 are preferably positioned so that the apparatus at each of the stations 11 is in its receiving position with the circuit 29, which includes a voice filter 33 and is connected to the lead 31, and the circuit 32, which includes one or more voice receivers such as the receivers 34 and loudspeaker 35 connected to the main amplifier 23. The circuits 29 and 32 may be regarded together as the voice receiving circuit when thus connected to the main amplifier 23.

The voice transmitting circuit 28 is shown as including a microphone 36 and the pre-amplifier 22. Preferably, I associate the switch 25 of the

circuit 21 with the microphone 36 so that it may be conveniently closed by the operator to energize the relay 24 which is then operative to position the switch arms 27 and 30 to connect the circuit 28 and the lead 31 to the main amplifier 23. The circuit 28 and the lead 31, when connected to the main amplifier 23, may be regarded as the voice transmitting circuit.

With the apparatus that I have thus far described, it will be apparent that the operator at any station 11 may, by closing the switch 25, talk to any and all stations provided with my apparatus and because of the bypass filters 13 and the voice filters 33, the line 10 may be used to carry voice frequencies without interference with or by the normal use of the telegraph instruments. My invention also permits the transmitting or receiving operator to vary amplification as circumstances require.

In the apparatus thus far described, it will be apparent that the nature of the voice receiver or receivers is a matter of choice. Where a loud-speaker 35 is used, particularly where it is located in a public part of the station, it is desirable to provide means for rendering it inoperative where confidential messages are being transmitted. I accomplish this result by arranging the receivers 34 and the loudspeaker 35 in parallel in the circuit 32 and between them, I provide a switch 37 under the control of the telegraph relay 12. The transmitting operator is, accordingly, able to include the loudspeaker 35 in the circuit 32 at each station 11 by holding closed the key of his telegraph instruments. My apparatus may be connected to the ground of the telegraph line or to a second line if desired.

From the foregoing illustration of my invention, it will be apparent that my invention is admirably adapted to a wide variety of uses of which its combination with the telegraph system of a railroad is but one example. It makes possible the transmission of audio-voice frequencies over a single, grounded line and where that line has other uses such as a telegraph line, it does not interfere with the transmission of telegraphic messages simultaneously with the transmission of voice frequencies. It provides simple and reliable apparatus allowing voice communication with greater speed than is possible with conventional telephone systems. It has the additional advantages of permitting simultaneous communication with several stations, variations at each station of the receiving or transmitting power, and greater safety as providing with the telegraph system alternate means of communication in the event of failure of either system.

What I therefore claim and desire to secure by Letters Patent is:

1. Apparatus for use at each station of a single, grounded telegraph line connecting tele-

graph instruments at each station, said apparatus comprising bypass filters between stations to bypass voice currents around said instruments to avoid interference with their use, inductance coils at terminal stations to prevent voice currents from entering battery circuits of terminal stations, a pre-amplifier, a main amplifier, a power supply for said amplifiers, an incomplete transmitting circuit connected to said line and to the ground thereof and including a voice transmitter and said pre-amplifier, an incomplete receiving circuit connected to said line and to said ground and including a voice filter and a voice receiver and switch means at each station to complete either of said circuits by including said main amplifier therein.

2. In apparatus for use at each station of a single, grounded line, said apparatus comprising a pre-amplifier, a main amplifier, a power supply for said amplifiers, an incomplete transmitting circuit connected to said line and to the ground thereof and including a voice transmitter and said pre-amplifier, an incomplete receiving circuit connected to said line and said ground and including a voice filter and a voice receiver, and switch means at each station to complete either of said circuits by including said main amplifier therein.

3. The apparatus of claim 1 in which the switch means has a normal position in which the receiving circuit is complete and a control circuit comprising a switch, a relay, to operate the switch to render the transmitting circuit complete and the receiving circuit incomplete.

4. The apparatus of claim 2 and means for varying the power to vary the effectiveness of transmission or reception.

5. In apparatus for use at each station of a single, grounded telegraph line connecting telegraph instruments at each station, said apparatus comprising a pre-amplifier, a main amplifier, a power supply for said amplifiers, an incomplete transmitting circuit connected to said line and to the ground thereof and including a voice transmitter and said pre-amplifier, an incomplete receiving circuit connected to said line and said ground and including a voice filter, a voice receiver, and a loud speaker, switch means to complete either of said circuits by including said main amplifier therein, and means operable at the transmitting station to connect or disconnect the loudspeaker from the receiving circuit of the receiving station.

6. The apparatus of claim 5 in which the voice receiver and the loudspeaker are in parallel in the receiving circuit and the receiving circuit includes a switch between the receiver and the loudspeaker, and a telegraph relay operates to close the switch.
